United States Patent Office

Des. 188,039
Patented May 31, 1960

188,039

END COVER FOR SUCTION CLEANER

Raymond Descarries, 3809 Carlton Ave., Montreal,
Quebec, Canada

Filed Sept. 24, 1958, Ser. No. 52,747

Term of patent 14 years

(Cl. D9—2)

FIG. 1

FIG. 2

FIG. 3

FIG. 4

Fig. 1 is a front perspective view of an end cover for a suction cleaner showing my new design;

Fig. 2 is a side elevational view thereof;

Fig. 3 is a rear elevational view thereof; and

Fig. 4 is a top plan view thereof.

The dominant features of my design reside in the portions shown in full lines.

I claim:

The ornamental design for an end cover for a suction cleaner, as shown and described.
